UNITED STATES PATENT OFFICE.

JAMES C. DOYLE, OF PORTLAND, OREGON.

DESIGN FOR AN AUTOTRUCK-BODY.

44,088.

Specification for Design.

Patented May 27, 1913.

Application filed January 19, 1912. Serial No. 672,211. Term of patent 7 years.

To all whom it may concern:

Be it known that I, JAMES C. DOYLE, a citizen of the United States, residing at Portland, in the county of Multnomah and State of Oregon, have invented a new, original, and ornamental Design for an Autotruck-Body, of which the following is a specification, reference being had to the accompanying drawing, forming part thereof.

The figure is a perspective view of an auto truck body showing my design.

I claim:

The ornamental design for an auto truck body, as shown.

Dated at Portland, Oregon, January 12th A. D. 1912.

JAMES C. DOYLE.

In the presence of—

L. M. LEPPER,

C. C. HALL.
